(57) **CLAIM**

The ornamental design for the keyboard with removable face plate, as shown and described.

DESCRIPTION

FIG. 1 is a top-front-right perspective view of a keyboard including a keyboard assembly and a removable face plate.

FIG. 2 is a bottom-back-left perspective view of the keyboard.

FIG. 3 is a top-front-right perspective view of the keyboard with removable face plate in which the elements are separated for clarity of illustration.

FIG. 4 is a top view of the keyboard with removable face plate.

FIG. 5 is a front view of the keyboard with removable face plate.

FIG. 6 is a back view of the keyboard with removable face plate.

FIG. 7 is a bottom view of the keyboard with removable face plate.

FIG. 8 is a right view of the keyboard with removable face plate; and,

FIG. 9 is a left view of the keyboard with removable face plate.

Broken lines shown in the drawings illustrate portions of the keyboard, and form no part of the claimed design.
